UNITED STATES PATENT OFFICE

2,515,458

CATTLE STANCHION

Victor E. Marr, Fredonia, Kans.

Application June 14, 1946, Serial No. 676,704

1 Claim. (Cl. 119—148)

1

This invention relates to new and useful improvements in cattle stanchions.

One object of my invention is to provide a cattle stanchion in which all of the stanchions may be released or locked simultaneously by the manipulation of a single control rod, but at the same time permitting any one or more of the stanchions to be operated individually by hand to permit the release or locking in of one or more of the cattle without interfering with the rest.

A further object of my invention is to provide a cattle stanchion in which the movable bars of the stanchion are held in closed or locked position by means of pivoted locking bars, which fall into place by gravity, but which may be raised into releasing position by means of novel wire catches having trip arms, and coacting lugs or fingers on the control rod.

A still further object of my invention is to provide a cattle stanchion whose length and capacity to accommodate any number of cattle, is limited only by the size of the barn.

Still another object of my invention is to provide a cattle stanchion in which the lugs or fingers that operate the wire catches are adjustable on the control rod, whereby the device may be adapted to the control of any desired number of cattle.

Still another object of my invention is to provide a cattle stanchion that is simple and economical in construction, and highly efficient and durable in use.

With the foregoing and other objects in view that will appear as the nature of my invention is better understood, the same consists in the novel features of construction, combination and arrangement of parts illustrated in the accompanying drawings and more particularly pointed out in the appended claim.

In the accompanying drawings, which are for illustrative purposes only and are therefore not drawn to scale:

Figure 1 is a front elevation of a cattle stanchion, constructed in accordance with my invention, with the pivoted bars of the stanchions in closed or locking position.

Figure 2 is a similar view, with the pivoted stanchion bars in open or releasing position.

Figure 3 is a plan view.

Figure 4 is an enlarged detail longitudinal section, taken through one of the pivoted locking bars and the upper end of the corresponding pivoted stanchion bar.

Figure 5 is a horizontal section, taken on line 5—5 of Figure 4, and Figure 6 is a vertical transverse section, taken on line 6—6 of Figure 4.

2

Referring to the drawings for a more particular description of my invention, and in which drawings like parts are designated by like reference characters throughout the several views,

5 A designates the frame of my improved stanchion, consisting of the corresponding laterally spaced base bars 1 and 2 and the corresponding laterally spaced top rails 3 and 4, between which extend and are rigidly secured at their lower and upper ends, the stationary uprights 5. The respective stanchions are spaced a suitable distance apart along the length of the frame A, and each stanchion consists of one of the stationary uprights 5 and a co-acting movable upright bar 6, pivoted at its lower end, as at 7, between the base bars 1 and 2 and formed at its upper end with a beveled head 8, which works between the top rails 3 and 4.

20 The movable members 6 of the stanchions are held in closed or locking position by means of the gravity locking bars 9, which are pivoted at one end, as at 10, to the upper ends of the adjacent stationary uprights 5 and fall into place between the top rails 3 and 4 of the stanchion frame A by their own weight. The pivoted locking bars 9 are formed on their bottom faces with the central depending catches 11, having the straight inner edges 12 and the inwardly beveled outer edges 13, which fit against the beveled heads 8 of the 25 movable stanchion bars 6 when the latter are in closed or locking position.

In carrying out my invention, the stanchion is provided with a longitudinal control rod 14, which extends approximately the length of the 30 frame A, and is adapted to slide longitudinally or end-wise in metal guides 15 and 16 fastened to the upper ends of the adjacent uprights 5. The control rod 14 is provided at one end with a crank handle 17 for manipulating the former 35 and which limits the movement of the control rod in one direction by contact with the metal guide 16.

The control rod 14 is provided at suitable points along its length with the transverse inwardly extending lugs or fingers 18 carried by the sleeves 19, which are adjustable on the control rod, the purpose of which will presently appear.

Wire catches 20, each constructed from a single piece of wire bent to form a central coiled body 45 portion 21, are swiveled to the transverse bearing pins 22 extending between the top rails 3 and 4 of the stanchion frame, and co-act with the pivoted bars 9 in holding the movable elements of the stanchions in closed position. As shown, each catch 20 comprises a horizontal arm 23 formed with a right-angularly bent end portion 24, which

bears or impinges against the upper end of the pivoted bar of the corresponding stanchion, and is also formed with a depending trip arm 25 formed at its lower end with a right-angularly bent portion 26.

Cross pins 27 between the top rails 3 and 4 form stops or rests for the horizontal arms 23 of the wire catches 20.

In practice, all of the stanchions may be simultaneously opened to release the animals by first turning the control rod 14 a fraction of a revolution by means of the handle 17, then sliding the control rod forwardly and engaging the fingers 18 with the opposite sides of the depending trip arms 23 and finally pulling back on the control rod. This final operation swings the right-angularly bent end portions 24 of the horizontal arms 23 of the wire catches 20 upwardly against the bottom edges of the outer ends 29 of the pivoted locking bars 9. This lifts the free ends of the pivoted locking bars 9 sufficiently to disengage the beveled edges 13 of the catches 11 thereof from the beveled heads 8 of the movable stanchion bars 6. At this stage in the operation, the further movement of the control rod 14 brings the fingers 18 in contact with the upper ends of the movable bars 6 of the stanchions, which are swung into open or releasing position. When in this position, the catches 11 of the pivoted locking bars 9 rest on the upper ends of the corresponding movable bars 6.

To simultaneously close all of the stanchions, the fingers 18 of the control rod 14 are engaged with the upper ends and opposite edges of the movable stanchion bars 6 and the control rod 35 pushed forwardly, when the pivoted locking bars 9 will automatically fall into place by gravity and lock said movable stanchion bars in place.

Any one or more of the stanchions may be opened independently of the control rod 14 to 40 release one or more animals merely by lifting one or more of the corresponding pivoted locking bars 9 by hand.

The sleeves 19 carrying the fingers 18 are

adjustable on the control rod 14 to permit the device to be adapted to any desired number or arrangement of the stalls.

From the foregoing description taken in connection with the drawings, it is thought that the construction, operation and advantages of my invention will be readily understood, without requiring a more extended explanation.

Having described my invention, what I claim as new and desire to secure by Letters Patent, is:

In combination with a frame, a stanchion comprising a stationary upright bar and co-acting pivoted bar, arranged in the frame, a pivoted locking bar adapted to hold the pivoted bar of the stanchion in closed or locking position, a control rod extending longitudinally of the frame and susceptible of end-wise movement with respect to the latter, and means for lifting the free end of the locking bar to release the upper end of the pivoted stanchion bar when a pull is exerted on the control rod, said means comprising a transverse inwardly extending adjustable finger on the control rod and a wire catch comprising a central coiled body portion swiveled to the top of the frame and having a horizontal arm formed with a right-angularly bent end portion bearing against the upper end of said pivoted bar and a depending trip arm disposed in the path of movement of said finger.
